BAYONET

Filed March 1, 1943

UNITED STATES PATENT OFFICE

2,367,212

BAYONET

Herbert C. Haag, Hohekus, N. J.

Application March 1, 1943, Serial No. 477,584

1 Claim. (Cl. 42—86)

(Granted under the act of March 3, 1883, as
amended April 30, 1928; 370 O. G. 757)

The invention described herein may be manufactured and used by or for the Government for governmental purposes without the payment to me of any royalty thereon.

The present invention relates to bayonets.

Among the objects of the invention are the following: simplification of manufacture, lessening of cost of production, increase in speed of production, elimination of forging operations in the production, and the application of punch press and stamping operations in the fabrication of bayonets.

The specific bayonet hereinafter described in detail as an example of an embodiment of the invention enables the accomplishment of the above stated objects.

In the accompanying drawing forming part of this description of an embodiment of the invention,

Fig. 1 is a side view of the bayonet attached to a rifle, the muzzle end only of the rifle being shown for purposes of simplifying the illustration.

Fig. 2 is a side view of the tang end of the bayonet with the hand grips removed, with the guard, pommel, and T-slot member in section and the bayonet and scabbard hooks in an intermediate position.

Fig. 3 is a plan view, partly in section, of the tang end of the bayonet.

Fig. 4 is a section on the line 4—4 of Fig. 2, but showing the hand grips applied to the tang.

Fig. 5 is a section on the line 5—5 of Fig. 2 and also showing the hand grips applied to the tang.

Fig. 6 is a section on the line 6—6 of Fig. 2, showing the guard, and ends of the hand grips, in elevation.

Fig. 7 is a view from below of the arm carrying the bayonet hook and scabbard hook.

Fig. 8 is a perspective view of the T-slot member which engages with the bayonet lug on the rifle.

Fig. 9 is a plan view of the T-slot member with the pommel.

Fig. 10 is a rear elevation of the pommel.

Fig. 11 is a side elevation of Fig. 10.

Referring in detail to the drawing, the bayonet includes a blade 1, a guard 2, a tang 3, a T-slot member 4, a pommel 5, pivoted arm 6 carrying bayonet hook 7 and scabbard hook 8, spring 9, and hand grips 10 and 11.

The blade 1, which extends forwardly from the guard 2, and the tang 3, which extends rearwardly from the said guard, are one continuous piece of steel, and are formed from a bar of steel

having the same or approximately the same width and thickness as the tang. The point of the blade and the cutting edges 12 and 13 of the blade are formed by grinding on one or both sides of the bar of steel, depending upon whether single or double bevelled cutting edges are desired.

In the fabrication of the blade and tang, long bars of steel of the width and thickness of the tang, or slightly larger in width and thickness than the finished article, are cut into lengths long enough to form the blade and tang as an integral piece. Each of these lengths or pieces is cut out or punched out on a punch press at the rear end of the tang (see Fig. 2) to provide the open space in the tang above the outline indicated by the letters A, B, C, D, E, F, G, H, J. If desired, the cutting of the bar into suitable lengths and the formation of said space by punching may be accomplished in a single punch press operation by the use of suitably made dies. From the foregoing it is to be noted that the blade and tang are integral; that in fact the tang is a continuation of the blade to the rear of the guard 2 and that the dimensions of the width and thickness of the blade at its rear end are the same as the corresponding dimensions of the tang from the guard 2 to the line HJ, where the width becomes irregular, due to the cut out part, but the thickness continues uniform from end to end of the tang.

The space at the rear end of the tang, produced by the above described cutting out operation, enables the fitting of the T-slot member 4 to the tang while remaining flush with the top thereof and the operation of the bayonet catch 7 within said space.

Referring more particularly to Figures 2, 3, 4, 5, 8 and 9, the T-slot member 4 is formed from a single piece of metal, such as steel, for example by blanking, punching and bending operations. In Figure 8 the formed T-slot member 4 is shown in perspective. It comprises a top portion 15 having the slot 16, and side portions 17 and 18 which turn inwardly, below the top, towards each other to form respectively bottom portions 19 and 20. These bottom portions stop short of meeting, to provide the slot 21 of sufficient width to accommodate the tang 3. The depending flange 22 proceeds downwardly from the bottom portion 20 and serves as a means for securing the T-slot member to the tang. The width of the flange 22, measured from the top of slot 21 to the bottom of the flange, in the embodiment of the invention shown, is the same as the width of the tang, at the pommel end, although it may

be somewhat less, so long as sufficient width is provided for securely attaching the T-slot member 4 to the tang 3. As will be seen from an inspection of Figure 8, the T-slot member 4 provides the T-slot 23 which continues lengthwise of the member, except that the slot 16 forming part thereof in the top of the member stops short of the end of the top of the member to provide the shoulder 24 (see Fig. 2).

The T-slot member 4 is assembled on the tang 3 as shown in Figures 2, 4 and 5, the flange 22 of the T-slot member 4 resting flat against the side of the tang 3 and being secured thereto by welding, brazing, silver soldering or riveting or in any other suitable manner.

The pommel 5 (see Figs. 2, 3, 9, 10 and 11) consists of a metal plate having a slot 25 and a T-slot 26 into the bottom of which the slot 25 opens. T-slot 26 has the same dimensions as T-slot 23 in T-slot member 4, except that it is bevelled at its entrance at 27 to facilitate entrance of the bayonet lug on the rifle. The length of the slot 25 from the bottom to the point where it opens into the T-slot 26 is the same as the width of the tang 3 at its end. The width of the slot 25 is such as to enable the pommel 5 to be fit over the end of the tang 3 as shown in Figures 2 and 3. The pommel 5 is welded, brazed or silver soldered to the tang 3.

The dimensions of the T-slot member 4, of the pommel 5, and of the cut-out portion at the end of the tang 3 are such as to enable these parts when assembled to occupy the relative positions shown in Figures 2 to 5. In this assembly T-slot 26 in pommel 5 registers with T-slot 23 in T-slot member 4, and both of these T-slots are of such shape and dimensions as to accommodate and engage with the bayonet lug 28 (see Fig. 1) on the upper band 29 of the rifle 30. The forward projecting lip 31 of the lug 28 fits beneath (see Fig. 2) the shoulder 24 when the bayonet is in fixed position on the rifle.

The guard 2 of the bayonet is made of steel by a punch press operation utilizing suitable dies. It consists of a rectangular piece of metal rounded at 40 at one end with an enlarged circular portion 41 at the other end. In this enlarged circular portion the barrel hole 42 is provided, within which the muzzle end of the barrel fits snugly with a sliding fit when the bayonet is fixed to the rifle as shown in Figure 1. A slot 43 is provided lengthwise and midway between the edges of the guard. The width of this slot is such as to enable the guard to be slid over the tang or blade into the position it is to occupy. The length of the slot 43 is much longer than the width of the tang or blade, and when the guard is assembled with the tang or blade this excess in length of the slot over the width of the tang or blade is equally, or about equally, divided at each end, as shown in Figures 2 and 6. The open portion at each end of the slot 43 is for the purpose of receiving the two scabbard mouthpiece hooks which are usually present on bayonet scabbards. The scabbard hook 8 (see Figs. 2, 6 and 7) is located in that open portion of the slot 43 which is on the cutting edge side 12 of the blade. The said open parts of slot 43 may be slightly chamfered on the blade side, as indicated at 44, to facilitate entry therein of the scabbard mouthpiece hooks. The guard 2 is fixed or secured in position by brazing, welding, silver soldering or riveting.

Arm 6 (Figs. 2 to 4) carries bayonet hook 7

and scabbard hook 8. An elevation of this arm is shown in Figure 2 and a bottom view is shown in Figure 7. This arm comprises two portions, which depart slightly from being 180 degrees from each other, as shown in Figure 2, with an enlarged portion 45 where the two portions of the arm meet. A hole 46 is provided through the enlarged portion 45, and through this hole passes the bolt 47 which holds the grips 10 and 11 on the tang. The size and shape of the hole 46 is such that the arm 6 pivots or rocks freely on the bolt 47.

The arm 6 lies externally of the tang 3 and rides against it during its motion in pivoting or rocking about the bolt 47 as a fulcrum or center. In the embodiment of the invention shown, that portion of the arm 6 which carries the bayonet hook 7 is somewhat longer than that portion which carries the scabbard hook 8, measured from the opening 46.

The bayonet hook 7 is shaped as shown in Figure 2 and is offset inwardly as shown in Figure 3 to bring it within the space in the tang defined by the outline BCDE. Hook 7 moves freely within this space and in T-slot 23 of T-slot member 4 when the arm 6 rocks on the bolt 47. The scabbard hook 8 is formed, as shown in Figures 2 and 7, with a checked or knurled thumb piece 48 which is offset inwardly from the end of portion 49 forming part of arm 6. The scabbard hook 8 extends forwardly from thumb piece 48. Thumb piece 48 and scabbard hook 8 are so disposed with relation to arm 6, that the thumb piece lies at some distance from the edge of tang 3 and hook 8 lies in slot 43 in the assembled condition. The purpose of spacing the thumb piece 48 from the edge of the tang 3 is to permit the arm 6 to be rocked by the pressure of the thumb thereon in disengaging the bayonet hook 7 or the scabbard hook 8 respectively from behind the bayonet lug 28 on the rifle or from the mouth-piece hook (not shown) on the bayonet scabbard.

Arm 6 with its enlarged portion 45 and with bayonet hook 7, portion 49, thumb piece 48 and scabbard hook 8 is formed from one piece of metal, such as steel, by suitable stamping, punching, bending and shaping or forming operations. These named parts, therefore, constitute an integral piece of metal, and by "integral" or "integrally formed" in the appended claims is to be understood integral not only in the sense of being made of or from one piece of metal but integral in the sense of constituting one body such as may be made up by welding, brazing or soldering separate parts together as one unitary structure.

A spring 9 is fixed at one of its ends to the tang 3 at 50 and presses against the part of the arm 6 that carries the scabbard hook 8, said spring urging the arm 6 clockwise as viewed in Figure 2. Spring 9 may be of the form shown in Figure 2 or of any other suitable form, or even otherwise positioned, so long as it accomplishes the purpose intended herein. In Figure 2 the parts are shown as if some pressure had already been applied to thumb piece 48, and this for the purpose of exposing more fully to view so much of T-slot member 4 as appears in said figure. The above mentioned clockwise motion of the arm 6 is arrested by part 19 (see Figs. 4 and 5) acting as a stop for said arm.

Hand grips 10 and 11 extend from the rear of guard 2 to the pommel 5, being recessed to pass beneath the portions 19 and 20 as shown in Figures 4 and 5. These hand grips are held in

position on tang 3 by means of a fillister head bolt 41 whose head and nut are respectively indicated by the numerals 51 and 52. This bolt passes through a hole in each hand grip and through a hole in the tang 3 intermediate its ends, and besides holding the hand grips in position, it also serves as the pivotal support, or center of rotation, of the arm 6. The inner surface of hand grip 10 fits flat against the tang 3 and the flange 22, a clearance cut being made on the inside of said hand grip to accommodate the flange 22. Hand grip 11 is provided with clearance cut 53 to accommodate arm 6 and spring 9, and with a clearance cut for portion 49 of arm 6, in such a manner as to permit motion of these without binding. These hand-grips may be made of wood, metal or of a suitable thermoplastic or thermo-setting composition.

What is claimed is as follows:

A bayonet comprising a blade and tang formed

5 of a continuous metal bar of substantially the same width and thickness, the tang portion of which has at least one substantially flat side and a cutaway portion at its rear end, a two armed lever pivoted intermediate its arms to the flat side of said tang for a rocking movement intermediate the ends of the tang, a bayonet hook on the rear arm of the lever and offset therefrom and extending into the cut-away portion of the tang into alignment with said tang, and a scabbard hook carried by the front arm of said lever, 10 an elongated member having a depending elongated flange secured to the tang on the side thereof opposite the lever, said member having elongated slots therein substantially the length of the member, said slots flanked by oppositely disposed bayonet lug engaging grooves and said member positioned in the cutaway portion of the tang.

HERBERT C. HAAG.
